Inventor.

UNITED STATES PATENT OFFICE.

WILLIAM MILTON, OF GUELPH, ONTARIO, CANADA.

TENSION-EVENER FOR YARN-WINDING MACHINES.

1,326,950.

Specification of Letters Patent.

Patented Jan. 6, 1920.

Application filed June 2, 1919. Serial No. 301,345.

To all whom it may concern:

Be it known that I, WILLIAM MILTON, a subject of his Majesty King George V of Great Britain, residing at Guelph, in the 5 county of Wellington and Province of Ontario, Dominion of Canada, have invented a new or Improved Tension-Evener for Yarn-Winding Machines, of which the following is a specification.

10 My invention relates to improvements in yarn winding machines in which a plurality of threads are unwound off vertical spools and combined and twisted into a single thicker thread and it consists in an attachment for putting a light intermittent tension on the threads as they leave the unwinding spools so as to prevent the threads from ballooning or snarling before they reach the twisting apparatus, thus giving 15 each thread an absolutely equal tension, tending to produce a perfect twisted yarn.

I illustrate my invention by the accompanying drawing, in which—

Figure I is a front elevation of my invention showing the pressure bar applying the tension to the thread as it leaves the unwinding spool.

Fig. II is a side elevation of the same showing the pressure bar resting against the 30 upper part of the hollow cores of four unwinding spools and applying equal tension to each of their respective threads.

Fig. III is an enlarged cross section of the pressure bar showing the construction 35 of same.

Similar letters of reference indicate similar parts in all the drawings.

If the yarn or thread is pulled rapidly off the evenly wound spool in a direction in 40 line with the center of the spool, the convolution of the thread will tend to spread or balloon as each coil or convolution is loosened. Said spreading or ballooning increases with the velocity with which the 45 thread is drawn off the spool.

The object of my invention is an apparatus that shall bring each convolution of thread up against the spindle of the spool against which it is unwound by means 50 of a pressure not strong enough to retard the thread but strong enough to bring each convolution at one point during the process

of unwinding between the spindle and the pressure bar. This intermittent control does not permit of more than one convolution of unwinding yarn being free at the same time and very largely controls the ballooning or spreading of the same. 55

A is the pressure bar composed of a semi-circular strip of wood (a) carrying a stiffened flap (b) of flannel or other similar substance. Said pressure bar is suspended by means of an adjustable curved lengthening bar formed of the parts B and B' joined together by a thumb screw working in a slot in the usual manner, thus enabling the length of said bar to be adjusted to the size of the spools carrying the yarn to be twisted. This lengthening bar is loosely suspended from a horizontal carrier bar C 70 located above and to the opposite side of the spindle to which the tension is to be applied.

It will thus be seen that the intermittent pressure or tension brought against the unwinding thread is that caused by the gravity or weight of the tension bar, although that could, if necessary, be increased by constructing the lengthening bar of spring material and rigidly connecting it to the horizontal carrier bar C, in which case any required tension could be brought to bear 75 on the unwinding threads.

The thread spools D are carried on vertical spindles located in sockets E carried 80 by the bearer bar F in the usual manner.

In operation it will be found that the act of unwinding is retarded at one point on all the threads operated upon by means of the pressure exerted by the pressure bar A 90 against the hollow core or spindle of the unwinding spool, and as the said pressure bar is suspended or pivoted from only one point it naturally follows that it comes to rest against the spindles with an equal pressure on each, sufficient to prevent any ballooning or snarling of the semi-twisted threads and producing an even resultant 95 yarn when the twisting is completed.

I claim—

The tension bar suspended from the body of a winding machine so as to rest lightly against the top of the stem of one or any number of unwinding spools set in a line,

said pressure bar being composed of an upper rigid portion carrying a semi-flexible flap or feather edge; the whole being suspended by a single adjustable lengthening bar from a suitable point on the machine so as to act by gravity or by means of the springy nature of the material of which the

said lengthening bar is composed substantially as hereinbefore described and illustrated in the drawings.

WILLIAM MILTON.
